[57] CLAIM

The ornamental design for a lipstick hutch, as shown and described.

DESCRIPTION

The “lipstick hutch” is for organizing a collection of lipsticks and lip liners. It may be wall-mounted or may rest on a flat surface.

FIG. 1. is a perspective view of the lip stick hutch.

FIG. 2. is a bottom view thereof;

FIG. 3. is a top plan view thereof;

FIG. 4. is a left side elevational view thereof;

FIG. 5. is a right side elevational view thereof;

FIG. 6. is a front elevational view thereof; and,

FIG. 7. is a rear elevational view thereof;
